FIRE EXTINGUISHER

Umberto Plagneri, San Francisco, Calif.

Application December 22, 1941, Serial No. 423,998

4 Claims. (Cl. 169—2)

This invention relates to a fire extinguisher which is particularly intended for use in connection with conduits or flues where a fire can be developed as in flues where grease, soot or other combustibles can collect and in garbage chutes and the like.

Most apartment houses are today provided with garbage chutes which extend from the ground floor upward, three, four or more stories, depending upon the height of the building. Each floor is provided with a covered hopper which connects with the garbage chute, so that the occupants of each floor may conveniently dispose of their garbage. Waste paper and other combustible rubbish is also dumped into the garbage chute and if some careless person should happen to throw a burning match or cigarette butt into the chute, a fire may start. In fact, so many fires are started in this manner that many cities are adopting stringent rules and taking every precaution toward fire prevention from this cause.

The object of this invention is to provide a sprinkler system in connection with flues, garbage chutes and the like whereby a sufficient amount of water may be applied to extinguish such a fire before it gains any considerable headway and further, to provide means actuated by the flames or heat developed when the fire starts to automatically turn on the sprinkler system and for sounding an alarm so that the water may be turned off when the fire is extinguished.

The invention is shown by way of illustration in the accompanying drawing in which:

Fig. 1 is a central, vertical, longitudinal section of a garbage chute such as employed in apartment houses; said section showing the application of a sprinkler system and a heat actuated means for automatically turning on the sprinkler system when fire is started, and for sounding an alarm.

Fig. 2 is the side elevation and partial section of the upper end of the garbage chute taken on line II—II, Fig. 1.

Fig. 3 is a partial cross section taken on line III—III, Fig. 1.

Fig. 4 is an enlarged view of a portion of the mechanism shown at the top of Fig. 1.

Referring to the drawing in detail and particularly Fig. 1, A indicates a garbage chute which may be cylindrical in cross section or of any other suitable shape. The garbage chute, if installed in an apartment house, will extend from the ground floor or basement to the uppermost floor and each floor will be provided with a hopper 2 through which garbage may be dumped into the chute. Formed in one side of the chute are a plurality of openings 3, which may be spaced apart any suitable distance, for instance—three inches or more. Partially covering each opening 3, is a deflector 4. Attached to the chute A is

a semi-circular tube or flue 5, see Figs. 1 and 3. The openings 3 register with the flue 5 and the flue extends the total length of the garbage chute. Disposed at the upper end of the garbage chute 5 is a head B which may be said to be T-shaped, as it extends crosswise of the garbage chute A and has openings 6 formed at each end to permit venting of the garbage chute and air circulation.

Disposed within the head B is a sprinkler head 10 C and connected therewith to supply water under pressure is a pipe 7. On the pipe is mounted a valve 8 which is normally closed. The valve is preferably of the rotary type, that is—a plug valve may be employed which, when rotated, 15 either opens or closes the same. If a plug valve is employed, the outer end thereof will be provided with a lever 9 and on the outer end of the lever will be secured a heavy weight 10. When the lever 9 and weight 10 assume the horizontal 20 or full line position shown in Fig. 1, the valve will be closed, and when the lever and weight is released and swings downwardly as will hereinafter be described, the valve will open and the sprinkler C will function.

Means must be provided for supporting the lever 9 and weight 10 in the horizontal position shown and this means is heat actuated to release the lever and weight when the sprinkler head is to function. In the present instance the lever 9 and weight 10 is supported by a second lever indicated at 11. This lever is pivoted as at 12 to a plate 14 supported by the head B. On one side of the lever 11 and adjacent to pivot 12 is an angle plate 15 and this engages a roller 16 secured to one side of the lever 9. The lever 11 is also provided with a weight shown at 17, while the opposite end of the lever is provided with a cord 18 which extends downwardly through the head B and the flue 5 to the lower end thereof 30 where it is anchored at the point indicated at 19.

The cord 18 may be constructed of any material which will part when subjected to the direct action of flames or heat developed thereby, thus, the cord 18 may be in the form of a fusible wire or links which will fuse and part when subjected to a certain temperature; or it may be constructed of any combustible material which will part when subjected to heat or flame 45 action.

The cord 18 has sufficient strength in tension to maintain the lever 11 in the horizontal position shown in Fig. 1 and thereby to support the lever 9 and the weight 10 in the horizontal 55 position, as roller 16 will be supported by the angle plate 15. On the other hand, if a fire starts at some point in the garbage chute, the flames and heat developed will be directed by the baffles or deflectors 4 into the flue 5 and the moment a certain temperature is developed, the

cord 18 will part, thus releasing the lever 11 and permitting the weight 17 to swing the lever about the pivot 12 to the dotted line position shown. In doing so, the lever 9 is released and the weight 10 will swing it to a vertical position, thus opening the valve 8 and turning on the sprinkler head. Water in the form of a shower is thus directed downwardly through the chute and the fire will be quickly extinguished. The water would, however, continue to flow unless an alarm is given so that the landlord or someone in charge will be notified, thereby permitting the water to be shut off and the mechanism reset.

In the present instance, an electric actuated bell 20 is provided. This may be supplied with current from a battery 21 or other suitable source of current supply. One wire 21a from the battery extends to the bell 20 as shown and another wire 22 connects the bell with the lever 11. A stop member, insulated from the plate 14 is provided at 23 and a third wire 24 connects this wire with the other terminal of the battery. Thus, when the lever 11 is released by parting of the cord 18, it will swing from the horizontal to the dotted line position shown and will thus close the circuit to operate the bell 20, thereby sounding an audible alarm. When this is sounding, the proprietor, manager, or other person in charge of the apartment house, will know that a fire has started in the garbage chute or other flue in which the mechanism is installed and that the sprinkler system has been turned on. That person will accordingly investigate and determine when the fire is properly extinguished. He may then proceed to the uppermost floor and close a valve indicated at 25 to temporarily close off the water. He may then lower a new cord, such as shown at 18, through the flue 5 and later attach the lower end thereof to the bottom anchor 19. He will then return the levers to the horizontal position and attach the cord to the outer end of the lever 11, when resetting of the mechanism will be completed and valve 25 may be again opened. A sliding door such as shown at 26 may be provided for convenient access to the anchor 19.

It may happen in an installation of this character that a fire may not occur over a period of a year or more. Corrosion is continuously taking place in water pipes and valves and if valve 8 is not operated over a long period of time, corrosion will take place and tend to resist opening of the valve when fire occurs. It is for this reason that a comparatively long lever 9 with a large weight 10 at the outer end is employed as the weight plus the lever arm will positively rotate the plug and open the valve even though considerable corrosion may have taken place.

The sprinkler head C is preferably of such size as to substantially close the upper end of the chute. Hence venting takes place through the openings 3 and the flue 5 and if a fire is started in the chute, the natural tendency will be to create a draft especially through the flue 5, thereby directing the heat and flames against the cord 18 and insuring positive release and quick operation of the valve 8 and sprinkler head C.

While this and other features of the invention has been more or less specifically described and illustrated, it should be understood that varying changes may be made within the scope of the appended claims. Similarly, it should be understood that the materials and finish of the several parts may also be varied and that while the invention has been described in connection with a garbage chute, it may obviously have other and

similar applications as in kitchen vents, flues, stacks and the like.

Having thus described and illustrated my invention, what I claim and wish to secure by Letters Patent is:

1. The combination with a flue or chute in which combustible material may collect of a sprinkler for directing water into the chute, a valve normally shutting off the water supply to the sprinkler, a flue adjacent the chute, openings formed in the chute in communication with the flue, means for directing flames and products of combustion when a fire occurs in the chute through said openings and upward through the flue, a heat destructible cord extending through the flue, said valve being maintained in closed position by said cord and means for opening the valve upon destruction of the cord.

2. The combination with a flue or chute in which combustible material may collect of a sprinkler for directing water into the chute, a valve normally shutting off the water supply to the sprinkler, a flue adjacent the chute, openings formed in the chute in communication with the flue, means for directing flames and products of combustion when a fire occurs in the chute through said openings and upward through the flue, a heat destructible cord extending through the flue, said valve being maintained in closed position by said cord and means for opening the valve upon destruction of the cord, and simultaneously sounding an alarm.

3. The combination with a flue or chute in which combustible material may collect of a sprinkler for directing water into the chute, a valve normally shutting off the water supply to the sprinkler, a lever on the valve, a weight on the outer end of the lever to open the valve, a second lever, a pivotal support for said second lever, a roller on the valve lever projecting over and engaging the second lever at one side of its pivot, said pin and second lever forming a support for the valve lever and its weight to maintain the valve in closed position, heat destructible means connecting with the second lever on the opposite side of its pivot to secure said second lever against pivotal movement, and a weight on the second lever to swing it about its pivot to release the valve lever and its weight when the heat destructible means is destroyed.

4. The combination with a flue or chute in which combustible material may collect of a sprinkler for directing water into the chute, a valve normally shutting off the water supply to the sprinkler, a lever on the valve, a weight on the outer end of the lever to open the valve, a second lever, a pivotal support for said second lever, a roller on the valve lever projecting over and engaging the second lever at one side of its pivot, said second lever forming a support for the valve lever and its weight to maintain the valve in closed position, a flue adjacent the chute, means for directing flames and products of combustion when a fire occurs from the chute into said flue, a heat destructible cord extending through the flue, means securing one end of the cord to the lower end of the flue, said cord being connected at its upper end to the second lever to secure said second lever against pivotal movement, and a weight on the second lever to swing it about its pivot to release the valve lever and its weight when the heat destructible cord is destroyed.

UMBERTO PIAGNERI.
